METHOD OF AND APPARATUS FOR ATOMIZING FUEL OIL

Application filed January 23, 1928. Serial No. 248,854.

This invention relates to atomizing methods and devices and more particularly to a method and apparatus for atomizing fuel oil for use in oil burners though it is noted that 5 the invention is not limited to oil burners nor in some respects even to the atomizing of fuel oil.

The basic principle of mechanical atomization involves the forcing of oil under pressure through a device designed so that it is capable of developing the maximum effect of centrifugal force which will cause the oil to whirl. The oil as it is forced through an orifice of a small diameter in a whirling state 15 and as it is released therefrom assumes a cone shape and centrifugal force then serves to break it up or atomize it into a fine spray. The greater the centrifugal force produced the greater is the cone or angle of dispersion 20 and the finer the atomization. As soon as the whirling cone of oil breaks up or atomizes, all rotation or whirling action practically ceases and the atomized oil is then in mechanically atomized state ready for its 25 proper mixture with air for combustion.

In my improved process the atomized oil as it leaves the orifice and which is moving forward but not whirling or rotating, is again caused to whirl when it once more assumes 30 the cone shape. It is then further atomized by centrifugal force and on completion of the second mechanical atomization, the finely atomized oil is met by and combined with a stream of air or steam and thereby atomized 35 again for the third time. This plurality of atomizations insures that the oil is broken up into as fine a degree of combustible mixture as possible and can homogeneously be mixed with air in order to obtain the final 40 combustible mixture. The present low pressure burners operating from 8 ounces to 2 pounds air pressure are all limited in heating capacity. The greatest capacity of the largest low pressure air burner on the market to- 45 day is about 30 gallons of fuel per hour and

requires about five horse power to furnish the air at two pounds pressure in order to atomize it. In my new process and apparatus, on account of the plurality of simultaneous mechanical atomizations, I am able to operate 50 the burner using less than one horse power to furnish the air for atomization for 30 gallons of fuel consumption per hour capacity, thereby increasing heating capacity with 55 greater economy of power consumption in accomplishing the desired ends.

Mechanical burners are being more and more recognized for their many advantages, but on account of their disadvantages which are principally first, high cost, the using of 60 oil under high pressure and the special auxiliary machinery necessary for this (compared with steam or air atomizing burners) the field of mechanical burner has been more or less limited, users of oil burning equipment preferring the less costly and 65 more the simple steam or air atomizing type, being willing to use a greater amount of power to atomize the oil rather than the complicated and expensive and delicate mechanical type. By the use of my process and apparatus all the advantages of mechanical burners are obtained and the disadvantages 70 do not exist as the oil is under ordinary pressure.

Further, it requires no special, auxiliary machinery and takes less power than any of the present mechanical or steam or air atomizing burners. The apparatus and method that 75 I have invented may be used for the reduction of ores, such as copper and the like, although it is not so limited, and it may further be utilized for any other type of metal reduction. Another use is for heating 80 purposes in large or small hot water and steam boilers. Accordingly, one of the main objects of my present invention is to cause a plurality of mechanical atomizations of fuel 85 oil and cause the final mechanical atomiza- 90

tion to be reatomized either by low pressure air, high pressure air or steam.

Another important object of this invention is to provide a simple and inexpensive apparatus whereby a plurality of mechanical atomizations can be obtained so that instead of using high pressures on oil a much lower one can be used, thereby saving power required for actual atomization.

Another principal object of this invention is to provide means within a simple device whereby a plurality of controlled oil feeding jets may be projected in a flat divergent path, thereby to form a fan flame in contradistinction to the annular torch type of nozzles heretofore utilized.

Another object of this invention is to provide in a burner only two cooperating parts, one directed to the utilization of air or steam as a means for atomizing the oil fuel into a combustion flame, and the other coating member operating as an oil jet block having a plurality of oil jet feeding means therein.

Another object of this invention is to provide means whereby adjustment between the air base portion and the jet nozzle block is obtained to increase or decrease the amount of oil fuel supply in proportion to a fixed and predetermined amount of air or steam supply for atomizing purposes.

Another object of my invention is to provide means for lockably adjusting the two main portions of my device in adjustable relative positions for operation, and to further provide means whereby atomization of the oil is accentuated by the cooperating action of the emitted air or steam jet and the cooperating air base nozzle therefor.

Another object of this process and apparatus is to be able to increase the size of the burner with but very little expense and to be able to handle oil of any viscosity as well as to be able to handle highly heated oil without having the burner puff intermittently.

Still another object of this invention is to provide a simple and inexpensive device in order to carry out this new process of atomizing the oil instead of the present complicated and expensive types of mechanical burners now on the market.

Still other objects of the invention will appear as the description proceeds; and while herein details of the invention are described and claimed, the invention is not limited to these.

An embodiment of the invention generally described above is shown in the accompanying drawing in which:—

- 60 Fig. 1 is a plan view of my device.
- Fig. 2 is a front elevation thereof.
- Fig. 3 is a sectional view taken on the line 3—3, Fig. 2 looking in the direction of the arrow.
- Fig. 4 is a sectional view, taken on the line

4—4, Fig. 2 looking in the direction of the arrow.

Fig. 5 is a plan view of the adjusting jet block removed from the holder.

In the drawings, Fig. 2 shows the device as comprising a holder or base portion 1, the same being provided with a boss 2 thereon. Into the boss is suitably tapped a pressure fluid admitting pipe 3. The pressure fluid may be steam or compressed air. The said base block 1 is further provided with a bridge 4 which is provided at its top with a boss 6 into which is mounted a locking stud 7 together with a lock nut 8 thereon, the purpose of which will be later described.

Said bridge 4 is further provided with a pair of preferably integral gibs 9—9, running transversely thereof. The interior of the bridge surfaces 10 including the gibs 9, are all machined. The lower surface 11 of the said block is also machined for the purpose of slidably and guidably receiving thereagainst an oil jet block which will now be described.

The oil jet block is a substantially rectangular metallic block, preferably in the form of a casting and is generally denoted by 12 in the drawings herein. It is provided at its rear with a fuel admission pipe 13 which is threadedly mounted into a suitable bore 14 therefor at the rear of said block 12. A port 15 connects the said pipe with a larger internally provided bore 16 which acts as a fuel oil chamber. From this last noted chamber a plurality of oil jet ports 17 are arranged on the under side thereof, so that they cooperate with the finished surfaces 11 of the base block 1. They act as oil emitting jets for causing the oil to take a relatively downward movement, as indicated by the arrows 18, Fig. 3.

In manufacture, this last noted jet block 12 is machined all over so as to provide finished surfaces therein including a pair of keyways 19—19, which cooperate with the keyways 9 in the bridge 4 to slidably guide the said block in adjustably relative movement over certain coordinating parts developed upon the surface 11 of the block 1, as will now be described.

By referring to Fig. 4 which is a sectional view of the block 1 showing the bridge portion removed, it will be noted that from the steam and air duct 3 there is developed a wide, shallow trough-like air or steam chamber 20, Figs. 2 and 3. Leading from this chamber 20, as is more fully shown in Fig. 4, there is a series of indented longitudinal air or steam channels 21, these being provided by a plurality of bridges 22 therebetween, thereby forming isolated separate passages leading from said air port to an elongated curvilinear indented fuel receiving atomizing chamber 23. This latter chamber is formed by being cut into the said block leaving a

sharp forward edge 24 at the front thereof. It will further be noted that the outer end terminations of this chamber 23 extend only within a short distance of the edge of the two outer or steam ports 21 whereby the edges of these ports are wiped clean by the passing high velocity air or steam, thereby preventing drip of fuel during operation.

From the foregoing construction, it will therefore be noted that steam or air emitted into pipe 3 passes upwardly into chamber 22, then spreads out and passes out at high velocity to atmosphere through ports 21. In the assembled construction shown in Fig. 3, in section, wherein there is shown the jet block 12 in assembled relative operative position with the base block 1, it will be noted that the jets 17 are directed downwardly into fuel receiving atomizing chamber 23. As the fuel is introduced under pressure the fuel passes downwardly along the surfaces and spreads out upon the wall of this jet where it is picked up by the stream of steam or air, as it passes out, in the direction of the arrow 25, and due 25 to the sharp edge 24, all liquid fuel emitted at this point is whipped out and dissipated in a finely atomizing floating fuel which when ignited forms a flame of clean combustion having a fan-shape form, as indicated by A, 30 Fig. 1, shown in dotted lines.

For the purpose of adjusting the amount of fuel that passes through jet hole 17, it becomes desirable to adjust the block 12 to and fro, so that more or less of the area of the 35 elongated jets 17 may cooperate with the rear edge 26 of the oil port 23, this being fully shown in Fig. 2, so that either the full area of these jets 17 may be utilized or only a minor part thereof, and this adjustment is 40 accomplished as follows:

The top screw 7 is released and the block 12 may be moved backwardly or forwardly to open or close the jets 17 to any desired opening, and in order to accomplish this adjustment, the rear end of the base 1, Fig. 1, is provided with two upstanding flanges 27 and 28. Flange 27 is provided with a set screw 29 which presses against the rear wall of the block 12 whereby to push the block inwardly 45 50 any desired distance, and the other upstanding flange 28 is provided with a shoulder screw 30 which is tapped into the rear end of the block 12, but is freely fitted within a bore 31, bored in said upstanding flange 28, so that 55 when this shoulder screw 30 is manipulated it can bore the block 12 rearwardly against the set position of the screw 29, both the screws 29 and 30 acting in the form of so-called "push-pull" screw locking adjustment.

It will therefore be noted I have provided this block 12 for adjusting purposes with a pair of screws to "push-pull" the block 12 in any suitable adjusted position and also a lock screw 7 to lock said block in the desired 65 operative position relative to the base 1 when

adjustment is satisfactory. The space between the flanges 27 and 28 is utilized as a clearance for the oil fuel pipe 13 so that adjustments as made permit this pipe to move forwardly or rearwardly with the jet block 70 movement.

In Fig. 2, it will be noted that the jets 17 are located in such a manner that their points of emission are shielded by the bridges 22 so that they are not subjected to the direct blast of emitted steam or air from port 21, thereby permitting the oil fuel as it emits from these ports 17 to travel downwardly over the surfaces of the duct 23 and to there spread out and meet the out-coming air or steam stream only when the fuel reaches the edge 24 of the nozzle proper.

To obtain the tertiary atomization of the oil there is provided just below the oil nozzle edge 24 a long narrow air slot 32 which is cut backwardly in such a manner as to permit air or steam from the pipe 3 to pass outwardly and join and commingle with the issuing atomized fuel stream from the upper nozzle.

Other objects of this stream of air or steam are to keep the outside of the curved lip 24 from carbonizing, and also to furnish auxiliary air (when air is used) for combustion purposes.

The operation of the atomizer or burner is 95 as follows:

Oil is supplied through duct 15 under pressure of from 2 pounds up, preferably the constant pressure would be between 50 and 75 pounds. This oil passes into reservoir 16 and is forced down through port 17. It then passes in front of bridge 22, then down and around and out of curved port 24 where the oil is struck by the air or steam which passes out through channels 21. The oil thus leaving reservoir 16 is wire-drawn and receives its first mechanical atomization on leaving the port 17. The oil upon striking the curved surface 24 in an atomized or divided state is given a whirling motion by passing from one side of and up the other side of the curved surface 24, so that when leaving the tip of the curved surface 24 the finely divided atomized oil is in the shape of small rapidly revolving whirls which are broken up by centrifugal action. The moment that these whirls leave the end of the curved tip 24 they are atomized by the laterally directed air or steam passing thru channels 21, and then struck by the stream of air or steam coming through slot 32 and there comingled and re-atomized. As a final result, a triple atomization is secured which insures the finest possible spray which can now be readily homogeneously mixed with 115 air for combustion.

It is obvious that by heating the oil to a high-degree better atomization will be obtained and a saving in oil made. It is also obvious that if the oil is heated to a point 120 125

between flash point and fire point that there will be no sputtering or puffing when the oil leaves the burners, as the reservoir being larger than the inlet pipe 15, the oil and gas 5 would be thoroughly mixed and then passed through port 17 under a constant pressure.

It will thus be noted that I have provided a burner which has a wide, non-annular stream emitting jet nozzle, together with 10 means, rearwardly and below said nozzle, for atomizing and admixing added air or steam for aid in combustion. I have also further provided a plurality of jets to a single burner slot shielded from direct action of the 15 atomizing air or steam. And that adjustments are provided whereby all of the jets may be adjusted, so as to cut more or less of their area into and out of operation, thereby to increase or decrease the amount of liquid 20 fuel supplied thereto, and enabling the use of oils of different viscosities by merely adjusting plate 4 so that the opening 17 is larger for heavier oils.

It should be understood that many and 25 various changes may be made without departing from scope of the invention as claimed in the broader claims herein appended.

What I claim is:

1. An oil atomizer comprising in combination, an oil jet block having an oil supply 30 chamber and a plurality of ports adapted to emit oil from said chamber in an atomized state, a pressure fluid block associated with said oil block having a pressure fluid supply 35 chamber therein, a trough-like chamber associated with said pressure fluid chamber, a plurality of bridges associated with said pressure fluid block cooperating with said oil block to form a plurality of independent 40 pressure fluid channels, an elongated indented oil receiving chamber associated with said channels adapted to receive the oil emitted from said oil jets and deflect said oil into the path of pressure fluid streams 45 flowing through said pressure channels whereby a fan-like stream of secondarily atomized oil is obtained, and adjusting means associated with said air block and cooperating with said oil block to vary the 50 quantity of oil supplied to said elongated chamber.

2. An oil atomizer as in claim 1 including an elongated slot disposed adjacent said elongated oil receiving chamber and adapted 55 to receive pressure fluid from said trough-like pressure fluid chamber and emitting said pressure fluid in an expanding fan-like stream, whereby said secondarily atomized oil stream is subjected to a third and complete atomization when it comes in contact 60 with said fan-like pressure fluid stream.

3. An apparatus comprising in combination, a member having an oil supply chamber and a plurality of ports, a second member 65 associated with said oil member having

a pressure fluid supply chamber therein, a plurality of bridges on said pressure fluid member cooperating with said oil member to form a plurality of independent pressure fluid channels, an elongated oil-receiving chamber associated with said channels adapted to receive oil emitted from said ports and deflect said oil into the path of pressure fluid streams flowing through said pressure channels whereby a fan-like stream of atomized oil is obtained. 70

4. In an apparatus as defined in claim 3, said second member including an elongated slot disposed adjacent said elongated oil receiving chamber and adapted to receive pressure fluid from said pressure fluid chamber and emitting said pressure fluid in an expanding fan-like stream, whereby said atomized oil stream is subjected to a complete atomization when it comes in contact with 80 said fan-like pressure fluid stream. 85

5. An atomizer comprising in combination, a member having an oil supply chamber and a plurality of ports, a second member associated with said first member having a pressure fluid supply chamber therein, means associated with said second member cooperating with said oil block to form a plurality of pressure fluid channels, means on said second member adapted to receive oil emitted from said ports and deflect said oil into the path of pressure fluid streams flowing through said pressure channels whereby a fan-like stream of atomized oil is obtained, additional means in said second member adjacent said oil-receiving means adapted to receive pressure fluid from said pressure fluid chamber and emit said pressure fluid in an expanding fan-like stream, whereby said atomized oil stream is subjected to a complete 100 atomization when it comes in contact with said fan-like pressure fluid stream. 105

6. An oil atomizer comprising in combination, an oil jet block having an oil supply chamber and a plurality of ports adapted to emit oil from said chamber in an atomized state, a pressure fluid block associated with said oil block having a pressure fluid supply chamber therein, a plurality of bridges associated with said pressure fluid block cooperating with said oil block to form a plurality of independent pressure fluid channels, an elongated indented oil receiving chamber associated with said channels adapted to receive the oil emitted from said oil jets and deflect said oil into the path of pressure fluid streams flowing through said pressure channels whereby a fan-like stream of completely atomized oil is obtained. 110

7. An oil atomizer comprising in combination, an oil jet block having an oil supply chamber and a plurality of ports adapted to emit oil from said chamber in an atomized state, a pressure fluid block associated with said oil block having a pressure fluid supply 120 chamber 125

chamber therein, a plurality of pressure fluid channels provided in said pressure fluid block, an oil-receiving chamber associated with said channels adapted to receive oil emitted from said oil jets and deflect said oil into the path of pressure fluid streams flowing through said pressure channels whereby a fan-like stream of secondarily atomized oil is obtained, an elongated slot disposed adjacent 10 said oil-receiving chamber and adapted to receive pressure fluid from said pressure fluid chamber and emitting said pressure fluid in an expanding fan-like stream, whereby said secondarily atomized oil stream is subjected 15 to a third and complete atomization when it comes in contact with said fan-like pressure fluid stream.

8. A process comprising, projecting in a common direction high pressure fluid streams 20 substantially limited to, and laterally extending in, a common plane slightly expanding the fluid; forming jets of fuel; atomizing the fuel of the jets and directing it into said pressure fluid along a line in said plane trans- 25 verse to the path of the fluid; and compressing the fluid along said line.

9. A burner comprising, means for projecting in a common direction high pressure fluid streams substantially limited to, and laterally 30 extended in, a wide plane; nozzles having outlets in said plane for injecting fuel through and transverse to said plane along a line substantially transverse to the path of the fluid; means for further atomizing the fuel after 35 it has passed through said plane and directing it back into said plane; and means for adjusting the size of said outlets.

10. An apparatus comprising, means for projecting in a common direction high pressure fluid stream substantially limited to, 40 and laterally extending in, a plane; jet nozzle means at said plane for directing jets of fuel; means for atomizing the fuel of the jets and directing it into said pressure fluid along a line in said plane transverse to the path of the fluid; compression means for compressing the fuel along said line; and means for adjusting the outlet of the compression means.

11. An apparatus comprising, means for projecting in a common direction high pressure fluid substantially limited to, and laterally extending in, a plane; jet nozzle means at said plane for directing jets of fuel; means for atomizing the fuel of the jets and directing it into said pressure fluid along a line in said plane transverse to the path of the fluid; compression means for compressing the fluid along said line; means for adjusting the outlet of the compression means and the nozzles 55 at said plane.

12. A process comprising, projecting in a common direction high pressure fluid streams substantially limited to, and laterally extending in, a common plane; forming jets of fuel; atomizing the fuel of the jets and directing it 60

into said pressure fluid along a line in said plane transverse to the path of the fluid; and disrupting and further atomizing the fuel just before it reaches said plane.

13. A process comprising, projecting in a common direction a plurality of streams of pressure fluid lying in a common plane; injecting fuel between said streams and through and transverse to said plane substantially along a line transverse to the plane path of 75 the fluid; and then directing the fuel back into said pressure fluid.

14. A process comprising, projecting in a common direction and plane a plurality of streams of pressure fluid, whereby low pressure spaces are formed adjacent to the streams; injecting fuel between said streams and through and transverse to said plane along a line transverse to the plane path of 80 the fluid; and atomizing the fuel in said low pressure spaces and directing it into said pressure fluid. 85

15. A process comprising, projecting in a common direction a plurality of thin streams of high pressure fluid in a common plane; directing jets of fuel between said streams transverse to said plane; atomizing the fuel of the jets and directing it back into said pressure fluid along a line in said plane transverse to the path of the fluid; and compressing the fuel along said line. 90 95

16. An apparatus comprising, means for projecting and slightly expanding in a common direction a plurality of spaced high pressure fluid streams substantially disposed in a common plane; jet nozzle means at said plane for directing jets of fuel; means for atomizing the fuel of the jets and directing it into said pressure fluid along a line in said plane transverse to the path of the fluid; compression means for compressing the fluid along said line; and means for adjusting the outlet of the compression means and the nozzles at said plane. 100 105

17. A process comprising, projecting in a common direction a plurality of thin streams of pressure fluid lying flatwise in a common plane; injecting fuel between said streams and through and transverse to said plane; and directing the fuel back into said pressure fluid. 110 115

18. A process comprising, projecting in a common direction a plurality of thin streams of high pressure fluid disposed flatwise in a common plane; directing jets of fuel between said streams transverse to the plane; atomizing the fuel of the jets and directing it back into said pressure fluid at an angle of about 45° and along a line in said plane transverse 120 to the path of the fluid; and compressing the fuel along said line. 125

19. A process comprising, projecting in a common direction high pressure fluid streams substantially limited to, and laterally extend- 130

ing in, a plane; directing fuel into said pressure fluid thereby to atomize the fuel; and directing a stiff wide sheet like stream of pressure fluid parallel to said plane and in said common direction, and near enough to cause the stream to further atomize the fuel.

20. A process comprising, projecting in a common direction pressure fluid streams lying in a thin plane; atomizing and injecting fuel through and transverse to said plane along a line transverse to the plane path of the fuel; further atomizing the fuel after it has passed through said plane and directing it back into said pressure fluid; and directing a wide thin stiff sheet of fluid under said plane substantially in said direction.

21. In combination, a base block having an elongated fuel-receiving trough-like atomizing chamber along the front edge of its upper face; said face having shallow, spaced pressure fluid channels parallel to said face and extending laterally into the atomizing chamber; a jet block engaging said face between said channels and intermediately closing said channels, and cooperating with the channels to form intermediately laterally closed separated fluid passages; said jet block having downwardly directed oil jet ports over the atomizing chamber.

22. In combination, a base block having an elongated fuel-receiving atomizing chamber along the front edge of its upper face; said face having pressure fluid channels extending laterally into the atomizing chamber; and a jet block intermediately closing said channels, and having downwardly directed oil jet ports over the inner edge of the atomizing chamber; said jet block being adjustable toward said front edge, to adjust the size of said ports.

23. A burner provided with an elongated fuel-receiving trough-like atomizing chamber having a transversely concaved bottom and a free outer edge; spaced parallel pressure fluid channels extending laterally into the inner edge of the atomizing chamber in a plane just above said outer edge; and downwardly directed oil jet ports over the inner edge of the atomizing chamber.

24. A burner provided with an elongated fuel-receiving trough-like atomizing chamber having an exposed outer edge; spaced parallel pressure fluid channels extending laterally into the inner edge of the atomizing chamber between and at the ends of the chamber; and downwardly directed oil jet ports over the inner edge of the atomizing chamber between said channels and away from said ends, whereby the pressure fluid wipes fuel from said ends.

25. In combination, a base block having an elongated fuel-receiving curved-bottomed trough-like atomizing chamber along the front edge of its upper face, said chamber terminating at its outer edge just below the

plane of said face; said face having shallow, spaced pressure-fluid channels extending laterally into the atomizing chamber; and a jet block intermediately closing said channels, and having downwardly directed oil jet ports over the inner edge of the atomizing chamber between said channel; said jet block being adjustable toward said outer edge, to adjust the size of said ports and the space between the jet block and said outer edge.

Signed at Plainfield, in the county of Union and State of New Jersey, this 21st day of January, A. D. 1928.
